UNITED STATES PATENT OFFICE

2,587,090

CAN OPENER

Ira G. Bandy, Detroit, Mich.

Application November 4, 1947, Serial No. 783,915

6 Claims. (Cl. 30—6.1)

1

This invention relates to an improved can opener.

It is an object of this invention to provide an improved can opener or perforator of the kind to be more particularly described hereinafter in which a metal can may have the top perforated by sliding the can inwardly relative to the supporting base.

Another object of this invention is to provide an improved can perforator of this kind having a slideable perforating member on a base which is actuated by the engagement of a can with an operating button rockably mounted on the base.

A further object of this invention is to facilitate the perforation of sealed cans of liquid contents or the like.

A further object of this invention is to provide a can opener of this kind having a slideable perforating member actuated by the engagement of a can to be perforated with an operating button and having perforating teeth slideably mounted on the perforating member whereby the device may be used for various sized cans and the engagement of the can with the device will properly push the perforating teeth on the surface to be perforated.

With the above and other objects in view, my invention consists in the arrangement, combination and details of construction disclosed in the drawings and specification, and then more particularly pointed out in the appended claims.

In the drawings,

Figure 1 is a side elevation partly broken away of a can perforator constructed according to an embodiment of this invention,

Figure 2 is a horizontal section taken on the line 2—2 of Figure 1,

Figure 3 is a vertical section taken on the line 3—3 of Figure 1,

Figure 4 is a vertical section taken on the line 4—4 of Figure 1,

Figure 5 is a bottom plan view of the sliding member removed from the assembly,

Figure 6 is a perspective view of the rock lever removed from the assembly,

Figure 7 is a fragmentary side elevation of a modified form of this invention, and

Figure 8 is a fragmentary side elevation partly in section of another modification of this invention.

Referring to the drawings, the numeral 10 designates generally a can perforator which is operated by the sliding engagement of a can top perforated with an operating button 11

2

which in turn actuates a perforating member 12 slidably mounted on the base.

The can perforating device 10 is formed with an L-shaped base 14 having a horizontal base arm 15 and a vertical arm 16 fixed to its lower end and to one edge of the base arm 15 by bolts 17 or other suitable fastening devices.

The vertical arm 16 is formed at its upper end with a pair of spaced apart arms 18 each formed with an inwardly opening groove 19 confronting the groove 19 on the other arm 18. Slidable members 20 having outwardly extending rails 21 are adapted to slidingly engage in the grooves 19 of the spaced apart arms 18.

15 A slot 22 is formed in the vertical arm 16 below the arms 18 and centrally of the width of the arm 16. A lever 24 is rockably mounted on the arm 16 by a pin 25 which engages across the slot 22 at the lower end thereof. The pin 25 rockably mounts the lever 24 for pivotal movement relative to the base 14 and vertical arm 16. The lever 24 is in the drawings shown as triangular having a vertical arm 26 and a lower horizontal arm 27.

20 An opening 28 is formed in the lower end of the lever 24 at the meeting point of the vertical and horizontal arms. The pivot pin 25 engages through the opening 28 for rockably mounting the lever on the base.

25 A slideable perforating member 29 is carried by the can perforator 10 between the arms 18 on the upper end of the vertical arm 16. The perforating arm or sliding member 29 extends horizontally from the arm 16 and is positioned 30 substantially parallel to the lower parallel arm 15 of the base 14.

The slideable member 29 is formed at one end with a depending member 30 having members 30 attached to the opposite sides thereof and engaging in the grooves 19. The lower end of the member 30 is formed with a pair of transversely spaced apart lugs 30a providing bearings for the pivot pin 32. The pivot pin 32 engages transversely through the member 30 and through the 35 slideable guides 20 and through one end of a link 34.

The upper end of the link 34 is rockably connected to the slideable member 29 and guides 20 through the pivot pin 32, and the other end of 40 the link 34 is pivotally connected by a pivot pin 35 to the opening 36 in the horizontal arm of the lever 24.

A horizontally extending operating arm 37 is rockably connected at one end to the opening 38 45 of the vertical arm 26 of the lever 24 by a pivot

pin 39. A button as 11 is fixed to or secured on the other end of the arm 37 for engagement with a can to be perforated.

The arm 37 is disposed in a position parallel to and spaced from the base 15 and perforating member 29. The arm 37 is supported in this position by a coiled spring 40 engaging about the arm along the length thereof. One end of the spring 40 abuts the outer face of the vertical arm 16 and the other end of the spring 40 engages about a reduced diameter stud 41 on the rear of the button 11.

In this manner, a can being pressed inwardly of the base 14 will engage the button 11 for rocking the lever 24 about the pivot 25. As the lever 24 is rocked, the link 34 is pulled downwardly carrying with it the guide member 20 and the perforating member 29.

A pair of pointed perforating teeth 42 are loosely carried by the sliding member 29 for sliding movement along the length thereof. The sliding member 29 is formed with an elongated slot 44 opening through the bottom thereof and a pair of elongated slots 45 opening through the opposite sides.

The slots 44 and 45 open to the interior of member 29. A carriage 46 having rollers 47 in the ends thereof supports the perforating teeth 42 on the sliding member 29. A depending arm 48 is fixed on the carriage at each end thereof between the rollers 47 for supporting the teeth 42 below the member 19.

The arms 48 are adapted to depend through the slot 44. The rollers 47 are adapted to slidably engage in the slots 45 on the sides of the member 29. A spring 49 is positioned within the slot 44 and abuts one of the arms as 48 of the carriage 46 at the outer end thereof.

The inner end of the spring 49 abuts the inner end of the slot 44 for continuously pressing the carriage 46 outwardly of the sliding member 29. As a can to be perforated is engaged within the member 10, the upper edge or surface of the can may be engaged with the teeth 42 for sliding the carriage 46 inwardly while the can is abutting the button 11 for sliding the perforated member 29 downwardly.

A substantially U-shaped supporting bracket as 50 is provided for securing the perforator 10 to a wall or fixed support. The side arms 51 of the bracket 50 are secured at their free ends to the sides of the vertical arm 16 by screws 52 or other suitable attaching devices.

The bight portion 54 of the bracket 50 may be formed with outwardly extending ears 55 through which screws 56 may be engaged for securing the bracket to a wall or other fixed support.

The perforating teeth 42 may be of any suitable size or shape even different from those shown in the drawings.

While I have shown a lever and linkage arrangement for actuating the slideable perforating member 29, a gear and rack arrangement may be used in connection between the arm 37 and the sliding member 29 for the same purpose.

In Figure 7 is a gear and rack arrangement which includes a spur gear 57 mounted on a pivot member 58 carried by a bearing 59. The bearing 59 is secured to the upright member 16a corresponding to the member 16 in Figure 1. A horizontally disposed and forwardly extending gear operator 37a is slideable through an opening 60 formed in the upright 16a and a spring 40a constantly urges the bar or rod 37a outwardly, the

outer end of the spring 40a bearing against a button or head similar to 11 in Figure 1.

The rear end of the rod 37a is connected to a crank 61 which is fixed relative to the spur gear 57. A slideable perforating arm 29a is disposed above the operator 37a and is slideable in an upright guide 62 which is fixed to a rearwardly extending arm 63 carried by the upright 16a.

A vertically disposed toothed rack 64 is fixed 10 at its upper end to the slide arm 29a and is adapted to mesh with the gear 57 so that rotation of the gear 57 in a counterclockwise direction will effect downward pull on the rack 64 and will pull the point carrying member or slide 15 29a downwardly into operative position.

Referring now to Figure 8, there is disclosed another modification of this invention including an upright member 16b similar to upright 16. The upright 16b has slidably extending there-20 through a lever operating bar 37b which is spring pressed outwardly by means of a spring 40b. The rod or operator 37b is pivotally connected as at 65 to the upper end of a rock lever or link 66 which is pivoted at its lower end as at 25 67 in a rearwardly projecting housing 68. The housing 68 is fixed to the rear side of the upright 16b. A vertically movable slide member 29b is disposed above the housing 68 and has associated therewith the elements disclosed in Figure 1 as-30 sociated with the slide member 29.

The slide member 29b has fixed thereto a de-35 pending bar 69 which loosely engages through an opening 70 formed in the top wall 71 of the housing 68. The arm or bar 69 is pivotally se-40 cured as at 72 to one end of a rock lever 73 which is pivotally mounted between the ends thereof as at 74 in the lower portion of the hous-45 ing 68.

The forward end of the rock lever 73 is piv-40 otally connected as at 75 to one arm 76 of a bell crank 77. The other arm 78 of the bell crank 77 is pivotally secured as at 79 to the lever 76 above the pivot 67. The bell crank 77 is piv-45 otally secured as at 80 to the upper end of a rocking link 81 which is pivoted as at 82 in the lower portion of the housing 68.

I do not mean to confine myself to the exact details of construction herein disclosed, but claim all variations falling within the purview of the 50 appended claims.

Having thus described my invention, what I claim is:

1. A can perforator comprising a base, a vertical arm on said base, a horizontally disposed 55 perforating member slidably carried by said arm, can piercing means carried by perforating member, an elongated toothed rack fixed relative to said perforating member and depending therefrom, a spur gear rotatably carried by said arm, 60 and meshing with said rack, and a spring pressed operating member operatively connected to said gear and disposed below said perforating member adapted upon movement thereby by a can sliding horizontally on said base to rotate said 65 spur gear and effect downward movement of said perforating member to pierce the can.

2. A can perforator comprising a base for supporting a can to be perforated, a vertically disposed member arranged adjacent one end of said base and fixedly secured to said base, a horizontal member positioned transversely of said member adjacent the other end thereof above and spaced from said base and mounted on said vertical member for limited up and down movement, 70 a can-perforating member adapted to engage the

top of a can when supported on said base mounted on said horizontal member for movement toward and away from said vertical member, means operatively connected to said horizontal member for effecting the up and down movement of the latter, and actuating means positioned transversely of said vertical member intermediate its ends operatively connected to said means and engageable upon forcible contact of the side of a can whose top is to be punctured to thereby cause down movement of said horizontal member and penetration of the top of a can when supported on said base.

3. A can perforator comprising a base for supporting a can to be perforated, a vertically disposed member arranged adjacent one end of said base and fixedly secured to said base, a horizontal member positioned transversely of said member adjacent the other end thereof above and spaced from said base and mounted on said vertical member for limited up and down movement, a can perforating member adapted to engage the top of a can when supported on said base mounted on said horizontal member for movement toward and away from said vertical member, means operatively connected to said horizontal member for effecting the up and down movement of the latter, actuating means positioned transversely of said vertical member intermediate its ends operatively connected to said means, and engageable upon forcible contact of the side of a can whose top is to be punctured to thereby cause down movement of said horizontal member and penetration of the top of a can when supported on said base, and spring means operatively connected to said actuating means for urging said vertical member in its up movement position.

4. A can perforator comprising a base for supporting a can to be perforated, a vertically disposed member arranged adjacent one end of said base and fixedly secured to said base, a horizontal member positioned transversely of said member adjacent the other end thereof above and spaced from said base and mounted on said vertical member for limited up and down movement, a can perforating member adapted to engage the top of a can when supported on said base mounted on said horizontal member for movement toward and away from said vertical member, an upstanding lever positioned transversely of said vertical member and mounted intermediate its ends on said vertical member for pivotal movement about an axis transverse of said vertical member, an upstanding link positioned adjacent said lever and having the lower end pivotally connected to the lower end of said lever, a guide block arranged adjacent the upper end of said link and mounted in said vertical member for up and down movement, a lug depending from said horizontal member adjacent said vertical member, means pivotally connecting said block, lug, and the upper end of said link together, and a pin positioned transversely of said vertical member intermediate its ends and having one end pivotally connected to the upper end of said lever and engageable upon forcible contact of the side of a can whose top is to be punctured to thereby cause down movement of said horizontal member and penetration of the top of a can when supported on said base.

5. A can perforator comprising a base for supporting a can to be perforated, a vertically disposed member arranged adjacent one end of said base and fixedly secured to said base, a horizontal

member positioned transversely of said member adjacent the other end thereof above and spaced from said base and mounted on said vertical member for limited up and down movement, a can perforating member adapted to engage the top of a can when supported on said base mounted on said horizontal member for movement toward and away from said horizontal member, a rotatable gear carried by said vertical member, a vertically disposed gear rack dependently carried by said horizontal member and in meshing engagement with said gear, an upstanding crank arm having the lower end fixedly secured to said gear, and a pin positioned transversely of said vertical member intermediate its ends and having one end pivotally connected to the upper end of said crank arm, and engageable upon forcible contact of the side of a can whose top is to be punctured to thereby cause down movement of said horizontal member and penetration of the top of a can when supported on said base.

6. A can perforator comprising a base for supporting a can to be perforated, a vertically disposed member arranged adjacent one end of said base and fixedly secured to said base, a horizontal member positioned transversely of said member adjacent the other end thereof above and spaced from said base and mounted on said vertical member for limited up and down movement, a can perforating member adapted to engage the top of a can when supported on said base mounted on said horizontal member for movement toward and away from said vertical member, a housing positioned on one side of said vertical member and below said horizontal member and fixedly secured to said vertical member, a first upstanding lever positioned within said housing adjacent said vertical member and having the lower end pivotally supported in said housing, an upstanding link positioned in said housing adjacent to and spaced from the lower end of said lever and having its lower end pivotally supported in said housing, a bell crank positioned adjacent the upper end of said link and pivotally connected intermediate its ends to the upper end of said link, one end of said bell crank being pivotally connected to said lever, a second lever positioned adjacent the other end of said bell crank and having one end pivotally connected to the other end of said bell crank, an upstanding bar positioned within said housing adjacent the other end of said second lever and having the upper end dependently supported on said horizontal member and having the lower end pivotally connected to the other end of said second lever, and a pin positioned transversely of said vertical member intermediate its ends and having one end extending into said housing and pivotally connected to the upper end of said first lever and engageable upon forcible contact of the side of a can whose top is to be punctured to thereby cause the down movement of said horizontal member and penetration of the top of a can when supported on said base.

IRA G. BANDY.
